(57) **CLAIM**

The ornamental design for a watch hand, as shown and described.

DESCRIPTION

FIG. 1 is a front perspective view of a watch hand according to my new design in a state in which it is positioned in a watch case;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In the drawings, the broken lines represent environmental structures that form no part of the claimed design.
